(57) **CLAIM**

The ornamental design for a single-wheel motorcycle trailer collapsible for storage, substantially as shown and described.

DESCRIPTION

FIG. 1 is a perspective view of a single-wheel motorcycle trailer collapsible for storage in accordance with the present invention, shown in an open state for towing behind a vehicle and transporting one or two motorcycles thereon; FIG. 2 is a right side view thereof; FIG. 3 is a left side view thereof; FIG. 4 is a front elevational view thereof; FIG. 5 is a rear elevational view thereof; FIG. 6 is a top plan view thereof; FIG. 7 is a bottom plan view thereof; and, FIG. 8 is a perspective view thereof, shown in a collapsed state for storing the trailer in a confined space when not use, with the support braces being rotated clockwise (with respect to the view of FIG. 1) into a collapsed storage position.

The broken lines shown in FIGS. 1 through 8 are for illustrative purposes only as optional equipment, and form no part of the claimed design.
